COUNTERBALANCED END DOORS FOR DROP END GONDOLA CARS

Ernest G. Goodwin, Toledo, Ohio, assignor to Unitcast Corporation, Toledo, Ohio, a corporation of Ohio

Application September 25, 1951, Serial No. 248,227

11 Claims. (Cl. 105—406)

This invention relates to gondola cars and more particularly to gondola cars provided with pivoted end doors.

The principal object of the invention, generally considered, is to provide an end door of a gondola car having at its lower portion hinged pintles which are adapted to engage corresponding pintles carried by the car sides, and to extend through the hinged pintles flat spring members so that the door, when assembled, will be counterbalanced to enable trainmen to raise the door from open to closed position.

Still another object of the invention is to provide a door assembly comprising the door body, hinged portions rigidly connected to the door body, hinged members rigidly connected to the car sides and spring members extending longitudinally of the door for giving to the door the desired torsion for counterbalancing the weight thereof.

Still another object of the invention is to provide in a drop end door of the character described a chamber adapted to house the spring members, said chamber being preferably substantially circular in section and adapted to house a spring retainer and torsioning means by which the torsion of the spring members may be finally adjusted.

Another object of the invention is to provide a method of mounting a drop end door of the character described whereby the spring members, torsioned as the door is dropped into place, may be further torsioned by first turning and then securing their inner portions relative to the door to adjust the torsion to the weight of the door.

Other objects and features of the invention will herein after more fully appear in the detailed description of the preferred embodiment of the invention illustrated in the accompanying drawings, in which:

Figure 1 is a vertical transverse section through a gondola car taken immediately in the rear of the upright position of the car door.

Figure 2 is an enlarged fragmentary section of the structure shown in Figure 1, partially in elevation and partially in section, certain of the structural parts of the car being omitted for the sake of clarity.

Figure 3 is a horizontal longitudinal section taken on line 3—3 of Figure 1, the direction of view being indicated by the arrows adjacent the ends of the sectional lines.

Figure 4 is a longitudinal vertical sectional view taken on line 4—4 of Figure 1.

Figure 5 is a longitudinal vertical sectional view taken on line 5—5 of Figure 1, the direction of view being indicated by the arrows at the end of the section line, and

Figure 6 is a transverse vertical sectional view taken on line 6—6 of Figure 4, the direction of view being indicated by the arrows adjacent the ends of the section line.

Referring now in detail to the drawings, the numeral 1 indicates the side sheets of a gondola car; the numeral 2, the corner posts; 3, the floor sheet; 4, 5 and 6, the end sill construction; and 7—7 are the center sills. The said parts being of the usual construction, a further description will be unnecessary.

Adjacent the car ends and riveted to the side sheets are

2

the hinged members 8, each of which is formed with a cylindrical boss 9, which is interiorly provided with tapering walls 10 leading to a flat, transverse slot or angular recess 11, the width of the slot being varied as shown in

5 Figure 2, the slot at the left-hand side of the door as illustrated in this figure being of sufficient width to receive two of the plate springs or torque bars 12, while the slot 13 in the other boss 14 is of sufficient width to receive four of the plate springs 12.

10 Secured to the outer flange 15 of the door 16 and to the transverse plate 17 of the door are bosses 18 which are adapted to pivotally embrace the bosses 9 of the hinged members 8, the inner ends 19 of the bosses 18 extend into the member or housing 20 which may be formed by bending the plate 21 so as to provide a substantially U-shaped portion having upstanding legs 22 and 23, the leg 22 overlapping the outer face of the sheet 17 of the door and being welded thereto by the weldment 24, as clearly shown in Figure 5. The leg 23 is adapted to abut the lower flange 25 of the transverse door plate 17 and is preferably secured thereto by the weldment 26.

There is provided in the flange 25 of the door a slot 27 as clearly shown in Figures 3 and 6. The position of the slot 27 transversely of the door is dependent upon the number of springs 12 which may be employed. If, as illustrated in the drawings, four springs are extended inwardly from the hinged pintle on the right side of the car and only two from that on the left side of the car, the slot 27 is positioned at a point where the torsional 20 effect on the sets of springs will be substantially equal. That is to say, the slot 27 will be placed much nearer the left side of the car than the right side. The foregoing is merely descriptive of the position of the slot and that position is also dependent upon the length and width of 25 the respective spring plates 12.

Seated within the member 20 and having an arm extending outwardly therefrom through the slot 27 is a casting or spool 28 having cylindrical end flanges 29, the latter having flattened portions or abutments 29a at either 30 side toward their upper edges to limit or restrict the movement of the casting relative to the member 20 to a partial rotary movement. The casting 28 is provided internally with slots or angular recesses 30 and 31, the slots 30 and 31 being of a size to receive the adjacent end of the respective springs 12. The arm or rigid lug 32 projecting outwardly from the center of the casting 28 is adapted to be received in the slot 27 and is provided with a curved recess 33 for receiving the end or adjacent side of a crowbar or the like, not illustrated. It will be understood, of course, that the car sides adjacent the upper end 35 of the door are provided with fastening means to maintain the door in vertical or closed position. Since these fastening means, while shown in Figure 1, do not constitute any part of applicant's present invention, no further reference will be made to the same.

55 To assemble the device the member 20 is formed; the casting 28 is inserted therein and moved to position so that the arm 32 is in alignment with the slot 27 in the flange 25 of the door. The member 20 is then welded to the door with the arm 32 extending through the slot 27.

60 The springs 12 are then inserted into the casting 28 and the door portions of the hinged pintle, i. e. the members 18, are then secured to the ends of the member 20. The hinged members 8 are then inserted over the end of the 65 springs and into the recesses in the members 18. The springs and hinged members are then held to the door and the latter is applied to a gondola car in the manner described in my Patent No. 2,580,760. In accordance with the method described in my Patent No. 2,580,760, the 70 hinged members 8, as the door is dropped into place, engage the floor of the car and by the weight of the door

are caused to rotate relative to the casting 28, thus tensioning or torque loading the spring members. After the hinged members 8 have been riveted in position, the door is swung open to ascertain whether or not sufficient torsion resides in the spring members to counterbalance the weight of the particular door. If it is found that there is insufficient torsion in the springs, a crowbar is then interposed between the door sheet 17 and the opening 33 in the arm 32 and the latter is forced rearwardly to rotate the casting 28 and is then welded in the desired position, thus increasing and finally adjusting the torsion of the springs 12.

Having now described my invention, what I claim and desire to secure by Letters Patent is:

1. In a drop end door for a gondola car, said door having a tubular housing at its lower portion and a slot opening into said housing, female hinge members carried by said door, and cooperating male hinge members to be secured in position to the side walls of the car after the door has been dropped down in final mounting position in the car, the combination of a plurality of torsion bars disposed in said housing and extending outwardly beyond the ends thereof, a spool disposed for partial rotation in said housing and having oppositely opening angular recesses to respectively receive the respective inner end portions of said torsion bars and being formed with an integral lug extending in said slot and movable therein in an arc about the axis of said housing and adapted to be secured in fixed position therein incident to the final adjustment of the torque load on said torque bars, said spool being formed with abutment faces limiting its partial rotary movement in both directions, said male hinge members respectively being formed with angular recesses to respectively receive the respective outer end portions of the respective torque bars, said male members after the door is dropped to its final position being held against rotation and with said spool giving said torque bars an initial torque load, and the mounting of the spool for free partial rotation permitting it to be given a partial rotation to give the final individual adjustment of the load on said torque bars, said lug being then secured against any movement in any direction in said slot.

2. In a drop door for a gondola car, said door having a tubular housing at its lower portion and a slot opening into said housing, door hinge members carried by said door, and cooperating car hinge members to be secured in position to the side walls of the car after the door has been dropped down in final mounting position in the car, the combination of a plurality of torsion bars disposed in said housing and extending outwardly beyond the ends thereof, a spool disposed for partial rotation in said housing and having oppositely opening angular recesses to respectively receive the respective inner ends of the respective torsion bars and being formed with an integral lug extending in said slot and movable therein in an arc about the axis of said spool and adapted to be secured in fixed position therein incident to the final adjustment of the torque load on said torque bars, said spool being formed with abutment faces limiting its partial rotary movement in both directions, and said car hinge members respectively being formed with angular recesses to respectively receive the respective outer end portions of the respective torque bars.

3. In a drop end door for a gondola car, said door having a tubular housing at its lower portion and a slot opening into said housing, door hinge members carried by said door, and cooperating car hinge members to be secured in position to the side walls of the car after the door has been dropped down in final mounting position in the car, the combination of a plurality of torsion bars disposed in said housing and extending outwardly beyond the ends thereof, a spool disposed for partial rotation in said housing and having oppositely opening angular recesses to receive respectively the respective inner end portions of said torsion bars and being pro-

vided with a lug rigid therewith and extending in said slot, said spool being formed with an abutment face limiting its partial rotary movement in one direction, and said car hinge members respectively being formed with angular recesses to respectively receive the respective outer end portions of the respective torque bars.

4. In a drop end door for a gondola car, said door being formed with a slot, door hinge members carried by said door, and cooperating car hinge members to be secured in position to the side walls of the car after the door has been dropped down in final mounting position in the car, the combination of a plurality of torsion bars disposed in said door and extending outwardly beyond portions thereof, a spool disposed for partial rotation in said door and having oppositely opening angular recesses to receive the respective inner end portions of said torsion bars and being provided with a lug rigid therewith and extending in said slot and movable therein in an arc and adapted to be secured in a fixed position therein incident to the final adjustment of the torque load of said torque bars, said spool being formed with an abutment face limiting its partial rotary movement in one direction.

5. In a drop end door for a gondola car, said door being formed with a slot, door hinge members carried by said door, and cooperating car hinge members to be secured in position to the side walls of the car after the door has been dropped down in final mounting position in the car, the combination of a torsion bar disposed in said door and extending outwardly beyond a portion thereof, a spool disposed for partial rotation in said door and having an angular recess to receive the inner end portion of said torsion rod and having a lug rigid with it and extending in said slot and movable therein in an arc and adapted to be secured in a fixed position therein incident to the final adjustment of the torque load of said torque bar, said spool being formed with an abutment limiting its partial rotary movement in one direction.

6. In a drop end door for a gondola car, said door being formed with a slot, door hinge members carried by said door, and cooperating car hinge members to be secured in position to the side walls of the car after the door has been dropped down in final mounting position in the car, the combination of a torsion bar disposed in said door and extending outwardly beyond a portion thereof, a spool disposed for partial rotation in said door and having an angular recess to receive the inner portion of said torsion rod and having a lug rigid with it and extending in said slot and movable therein in an arc and adapted to be secured in a fixed position therein incident to the final adjustment of the torque load on said torque bar.

7. Door mechanism for a drop end door of a gondola car, comprising a torque bar disposed in said door, said bar having an outer end extending outwardly beyond a portion of said door and anchored to a side of said car, a spool carried by said door intermediate sides thereof and disposed for partial rotation relative thereto, said spool having a slot receiving an inner portion of said torque bar, means for rotating said spool to adjust the torque load on said bar, and means for securing said spool against rotation relative to said door and thereby fixing the torque load on said bar.

8. In a method of mounting a drop door in a gondola car and adjusting the torque load of torque bars tending to move the door from open toward closed position, wherein, firstly, the door with the car hinge members associated therewith is manipulated into proper position with relation to a gondola car, secondly, the door with said car hinge members is lowered into position and simultaneously with the final stages of such lowering said car hinge members are partially rotated in one direction to twist said torque bars while the inner end portions of said torque bars are held against turning, and thirdly, the car hinge members are permanently secured in and to the car; the subsequent steps comprising turning the inner end portions of the torque bars in the reverse direction while

holding their outer end portions against turning to adjust the torque load of the torque bars in accordance with the weight of the particular individual doors, and securing the inner ends of said torque bars against rotary movement relative to said door.

9. In a method of mounting a drop door in a gondola car and adjusting the torque load of a torque bar tending to move the door from open toward closed position, wherein, firstly, the door with the car hinge members associated therewith is manipulated into proper position with relation to a gondola car, secondly, the door with said car hinge members is lowered into position and simultaneously with the final stages of such lowering one of said car hinge members is partially rotated in one direction to twist said torque bar while the inner end portion of said torque bar is held against turning, and thirdly, the car hinge members are permanently secured in and to the car; the subsequent steps comprising, turning the inner end portion of the torque bar in the reverse direction while holding its outer end portion against turning to adjust the torque load of the torque bar in accordance with the weight of the particular individual door, and securing the inner end of said torque bar against rotary movement relative to said door.

10. In a method of mounting a drop door in a gondola car and adjusting the torque load of torque bars tending to move the door from open toward closed position, wherein, firstly the door is manipulated into proper position with relation to a gondola car, and, secondly, the door is lowered into position and simultaneously with the final stages of such lowering the outer end portions of said torque bars are partially rotated in one direction while

their inner end portions are held against turning to twist said torque bars to a definite fixed standard degree; the subsequent steps comprising adjusting the torque load of the torque bars by turning the inner end portions of the torque bars in the reverse direction while holding their outer end portions against turning in accordance with the torque load required by the weight of the particular individual door, and securing the inner ends of said torque bars against rotary movement relative to said door.

11. In a method of mounting a drop door in a gondola car and adjusting the torque load of a torque bar tending to move the door from open toward closed position, wherein firstly, the door is manipulated into proper position with relation to a gondola car, and secondly, the door is lowered into position and simultaneously with the final stages of such lowering the outer portion of said torque bar is partially rotated in one direction while the inner portion thereof is held against turning to twist said torque bar to a definite fixed standard degree; the subsequent steps comprising adjusting the torque load of the torque bar by turning the inner portion thereof in the reverse direction while holding its outer portion against turning in accordance with the torque load required by the weight of the particular individual door, and securing the inner portion of said torque bar against rotary movement relative to said door.
